(57) **CLAIM**

The ornamental design for a skull-shaped motor vehicle shift light cover, as shown and described.

DESCRIPTION

This application claims priority to U.S. application Ser. No. 29/539,242, filed Sep. 11, 2015.

FIG. 1 is a perspective view of a skull-shaped motor vehicle shift light cover showing my new design;

FIG. 2 is another perspective view thereof;

FIG. 3 is a front elevational view thereof;

FIG. 4 is right side elevational view thereof;

FIG. 5 is a rear elevational view thereof;

FIG. 6 is a left side elevational view thereof;

FIG. 7 is a top plan view thereof; and,

FIG. 8 is a bottom plan view thereof.

The broken lines depict unclaimed portions and form no part of the claimed design.
